UNITED STATES PATENT OFFICE.

FREDERICK A. HOSCHKE, OF SPRINGFIELD, MASSACHUSETTS.

REPRODUCING INSTRUMENT AND ASSOCIATED MECHANISM.

1,373,732.

Specification of Letters Patent.

Patented Apr. 5, 1921.

Application filed May 10, 1918. Serial No. 233,719.

To all whom it may concern:

Be it known that I, FREDERICK A. HOSCHKE, a citizen of the United States, and a resident of Springfield, in the county 5 of Hampden and State of Massachusetts, have invented certain new and useful Improvements in Reproducing Instruments and Associated Mechanism, of which the following is a specification.

10 This invention relates to apparatus for starting various mechanisms, such as are adapted to operate during the operation of a reproducing instrument, simultaneously with the commencement of reproduction 15 from the instrument. While the invention is capable of general application, it finds one advantageous use as a means for setting in motion various mechanisms, as an automatic piano or the like, for example, immediately as an instrument, particularly a 20 phonograph, begins to reproduce sounds.

An illustrative example of one of the many uses, to which the invention may be put, is in the control of the motor of a 25 player piano so that the music produced thereby will be made to begin simultaneously with the music produced by a phonograph. The problem of synchronizing the talking machine with the automatic piano

30 has been attempted heretofore, as evidenced by the prior art. Effort has, however, been largely directed to regulating the speed of the one instrument relatively to the other so that the two will operate synchronously.

35 For example, many devices have been proposed, whereby the speed of the driving roll for the record sheet of the player piano is made to travel at a speed proportioned to that of the record-carrying table of the talking machine. Satisfactory and harmonious operation of two separately-operable musical instruments cannot, however, be achieved unless the music from both is made to commence simultaneously. Heretofore, as I am

40 aware, the record-sheet driving-roll of the piano and the record-carrying turntable of the phonograph have been caused to start simultaneously, but the simultaneous starting of such roll and turntable does not necessarily result in simultaneous starting of

45 the music from the two instruments. It is well known that in the ordinary phonograph the stylus rides idly in the groove of the record for varying and appreciable distances. For example, several revolutions 50 of the record are frequently necessary be-

fore the stylus is actuated to produce sounds. It will be obvious, then, that the desired results cannot be obtained by merely starting the two record-driving elements of 60 the two instruments simultaneously.

This invention has for its broad object to provide a means, whereby a separately-operable mechanism, such as an automatic piano, for example, may be controlled from 65 a reproducing instrument, as a phonograph, so that the mechanism may be started simultaneously with the production of sound from the phonograph irrespective of the time of starting of the phonograph record-propelling means.

Another object of the invention is to provide in a reproducing instrument, such as a phonograph, for example, means which may be accurately set to various predetermined 75 positions corresponding to the varying lengths of the idle or non-reproducing parts of records and which may be moved during the preliminary motion of the record so as to come into position to start, or 80 permit starting, of a separately-operable mechanism at the same time that the reproducing part of the record comes into play.

A further object of the invention is to provide in combination with a player piano 85 and a phonograph, a device associated with the latter and effective to disconnect the record-propelling motor of the piano from its source of supply during the preliminary motion of the phonograph record, said device being operable to connect the motor to 90 its source after the phonograph record has traveled a predetermined distance, the arrangement being such that the record sheet of the piano may be set in position to immediately cause reproduction on the starting of its motor, and said device may be set to start the motor after the phonograph record has completed its idle and non-reproducing movement.

100 Other objects and advantages will appear in the following description and in the appended claims.

The invention will be disclosed in an illustrative embodiment with reference to the 105 accompanying drawings, in which—

Figure 1 is a diagrammatical view of a reproducing instrument and a separately-operable mechanism controlled thereby in accordance with the invention;

Fig. 2 is a fragmentary plan view, with parts broken away, of a phonograph show-

110

ing the controlling device as applied thereto; and

Fig. 3 is a partial cross-sectional view taken on the line 3—3 of Fig. 2.

5 Referring to these drawings in detail, A indicates generally the reproducing instrument, which in this instance is a phonograph, and B represents generally a separately-operable mechanism, which, as an 10 illustrative example, may be considered as a player piano, although, obviously, various other mechanisms may be substituted, as will readily occur to those skilled in the art. The phonograph A and player piano B, being 15 both well understood in the art, the present illustration has been confined largely to a diagrammatical representation of such parts of the two instruments as are necessary to an understanding of the present invention. It 20 is to be understood that each of the instruments A and B may be of any suitable or desirable form, and the types shown are merely illustrative of one suitable form of each instrument with which the invention 25 may be used.

The essential parts of the phonograph A which need to be considered are the turntable or record carrier *a*; the turntable driving shaft *b*, which is driven by the usual 30 motor (not shown); the record *c*; the swingingly-mounted tone-arm *d*; and the reproducer *e*, which is carried by the tone-arm and provided with a suitable stylus (not shown). All the elements enumerated are 35 now too well known to require further description herein.

The essential elements of the player piano B will next be briefly described. The music sheet or record *f* is carried by the usual rolls 40 *g* and *h* and travels over a suitable tracker-bar *i*. The music sheet propelling means comprises a motor *j* of any suitable type and the usual driving connections between the motor *j* and the rolls *g* and *h*, which connections are shown in conventional form 45 only and are indicated generally by reference letter *k*. Connections *k* are arranged in the usual manner so that either roll *g* and *h* may be driven, the former being driven 50 to wind the sheet *f* thereon during the production of music and the latter being capable of rewinding the sheet, all in a now well-understood manner. The motor *j*, as illustrated, is of a known type operable by atmospheric pressure which is made effective 55 for this purpose by creating a partial vacuum in the motor. A suitable pipe *l* is adapted to be connected to a suitable suction means to cause operation of motor *k*.

60 According to the invention, however, the pipe *l* is not connected directly to the suction means but leads to a chamber 5 in a casing 6. Adjacent chamber 5 is a second chamber 7, and the two chambers may 65 communicate by an opening 8. From chamber

7 a pipe 9 leads to a suitable suction means (not shown). Communication between chambers 5 and 7 is controlled by a valve 10 which is slidably mounted in casing 6 and is connected to a bellows 11 for actuation in a manner to appear. The degree of opening of valve 10 is limited by the engagement of a buffer-block 12 on valve 10 with the casing 6. The latter, it is to be understood, is entirely closed so that chambers 5 75 and 7 and opening 8 may form substantially air-tight connections between the pipes 7 and 9.

The bellows 11 is part of a so-called "pneumatic" and is constantly in communication with a chamber 14. Adjacent the latter is a chamber 15 from which a pipe 16 leads to a suitable suction means (not shown), whereby a partial vacuum may constantly exist in chamber 15. An opening 17 80 permits communication between chambers 14 and 15 when a valve 18 is open, whereby the air in bellows 11 may be exhausted through pipe 16. The exhaustion of the air in the bellows will collapse the latter and thereby move valve 10 to close the opening 8. Thus, the motor *j* will be cut off from communication with its suction means and cannot operate to move the music sheet *f*. Adjacent the chamber 15 is a chamber 20 95 from which a flexible pipe 21 leads to the phonograph A for association with a controlling device later to be described. The partition between chambers 15 and 20 includes a movable diaphragm 22 which is 100 suitably located to actuate the described valve 18, as will appear. A relatively small opening or bleed hole 23 permits constant although restricted communication between the chambers 15 and 20. The chambers 14, 105 15, and 20 are entirely inclosed, as should be well understood. That end of pipe 21 associated with the phonograph A may, as will appear, be opened or closed to the atmosphere. When closed, chamber 20 is exhausted through bleed hole 23, and the movable wall 22 is held in its normal position to seat valve 18. When opened, atmospheric air enters chamber 20 and forces the movable wall 22 upwardly to engage and lift the 115 valve 18, whereby communication may be established between the chambers 14 and 15 and bellows 11 may be collapsed. Further description of the "pneumatic" for operating the valve 10 is thought unnecessary, as 120 such devices are well understood by those skilled in the art.

Referring now to Figs. 2 and 3, it will be seen that the described flexible pipe 21 leads to and has its end secured to a frame 25 125 which is suitably fixed in the phonograph A. The frame 25 carries an upstanding stud 26 which is arranged parallel with and closely adjacent to the driving shaft *b* for the turntable *a*. Loosely mounted on stud 26 is a 130

sleeve 27 and adjustably secured to the latter is an arm 28 which carries a valve 29 adapted to engage and close the end of the flexible pipe 21. Also adjustably secured to sleeve 27 and below arm 28 is a lever 30 by means of which valve 29 may be swung away from pipe 21 to various positions. Lever 30 is adapted for manual actuation in one direction to open the end of pipe 21 and has its free end offset, as shown in Fig. 3, to lie in the path of a pin 31 which is secured in upstanding relation to a horizontal rod 32. The latter is slidably mounted on the phonograph casing and has a part extending through the latter which is provided with a button 33 for convenient actuation. Passing transversely through rod 32 is a pin 34, and the ends of the latter are arranged to ride on two spaced pads 35 of suitable material, such as felt, to prevent turning of rod 32. A spring 36 is coiled around rod 32 and is interposed between pin 34 and the casing of phonograph A to normally hold the rod in the illustrated position, wherein button 33 engages a part of the casing and limits the inward movement of rod 32. The outward movement of the latter is limited by the engagement of pin 34 with an upstanding pin 37 fixed in the casing of phonograph A.

The arm 28 is movable in the other direction to close the end of pipe 21 by means controlled by the movement of the record *c* of the phonograph A. In the illustrated embodiment of the invention, such means consist of a gear 39 fixed to the described sleeve 27 below the lever 30, and a pin 40 secured to and depending from the flange of turntable *a*, as shown in Fig. 3. The arrangement is such that pin 40 may engage gear 39 once during each revolution of turntable *a* and move the gear one step. Gear 39 has one tooth cut away leaving a space 41, which when positioned as in Fig. 2, permits pin 40 to freely pass without actuating the gear. Thus, when valve 29 is in the illustrated position, wherein the end of pipe 21 is closed to the atmosphere, the space 41 is so positioned as to permit free revolution of the turntable *a* without further actuation of gear 39.

As already described, rod 32 is adapted for manual actuation to swing valve 29 to various predetermined positions. Gear 39 is thus moved in a clockwise direction, as viewed in Fig. 2, which brings teeth of the gear into position to be engaged by pin 40. Obviously, the gear 39 must be moved by definite increments in order that it be so positioned that pin 40 will properly mesh with the gear. To permit accurate setting of the gear, a pointer 42 is pivoted at 43 to the casing of phonograph A, and at one end has a slot to engage the described pin 31 on the slidably rod 32. The other end of the

pointer plays over a graduated scale, which in this instance comprises an arcuate row of spaced pins 44. When pointer 42 is swung to the left to the next pin 44, gear 39 will be set for proper engagement by pin 40 70 and will be moved thereby into the illustrated position after the turntable *a* has completed one revolution. The pins 44 thus indicate the number of revolutions of the turntable *a* necessary to move valve 29 into 75 closed position.

The turntable *a* is provided with a suitable mark 45 to coöperate with a mark 46 on the casing of phonograph A so that the operator may accurately set the turntable 80 to a predetermined position, wherein it is assured that the pin 40 will lie in the illustrated position. The record *c* may have a mark 47 thereon which, when alined with the mark 46, assures a definite predetermined positioning of the record on the turntable.

In using the apparatus described, the number of idle turns in the sound groove of record *c* is first determined, either by actual trial or from appropriate markings on the record itself indicating the number of such turns. Obviously, the apparatus may be designed so that the valve 29 may be moved into position to close pipe 21 after 95 any desired number of revolutions of turntable *a*, and I do not intend to limit myself to any particular number of such revolutions. Furthermore, I have shown an arrangement, whereby the valve 29 is moved 100 one step on each complete revolution of the turntable, for, as a practical matter, I have found that fractional parts of idle convolutions of the sound groove of the record do not appreciably affect the accuracy of the 105 apparatus. It is, however, obvious that the apparatus may readily be arranged for as accurate a setting as desired, and simply because I have shown, as an illustrative example, an arrangement whereby gear 39 is 110 moved one step on each rotation of turntable *a*, I do not intend to limit myself to such arrangement.

Moreover, in order to care for fractional parts of idle convolutions of the sound 115 groove with the illustrated form of the apparatus, I may provide, instead of the single graduation 45 on the table *a*, a series of graduations, as 45, 45', 45'', and 45''' any one of which may be set to register with the 120 mark 46. Thus, for example, if the record has a fractional idle convolution, as three quarters of a convolution, for example, the graduation 45''' may be set to register with mark 46 instead of graduation 45, as formerly. By so doing, the pin 40 will be advanced a quarter of a revolution in a clockwise direction (Fig. 2) so that it will engage and actuate the gear 39 after the table *a* has turned three quarters of a revolution. Simi- 125 130

larly, the graduations 45' and 45² when set to the mark 46 will permit the gear to be actuated after a quarter and a half revolution, respectively, of the carrier *a*. The 5 mark 47 on the record is, however, always set opposite the mark 46.

In operation, the operator sets the music sheet *f* with relation to the tracker-bar *i* so that, immediately on operation of motor *j*, 10 the piano will commence its production of music. The operator sets the record *c* and turntable *a* so that the marks 47 and 45, respectively, thereon aline with the mark 46. Knowing the number of idle convolutions 15 of the sound groove of record *c*, say three, for example, the operator pulls rod 32 outwardly until pointer 42 comes to the desired pin 44, as the fourth pin to the left in Fig. 2. Immediately the operator releases rod 32, 20 the latter is moved back into the illustrated position by spring 36, without, however, moving the lever 30. Thus, gear 39 has been moved a definite angular distance in a clockwise direction which is known to be such 25 that a definite number of rotations of the turntable *a* in a clockwise direction will be necessary to return the gear into the illustrated position, wherein valve 29 closes the end of pipe 21. The operator then places 30 the stylus in the first convolution of the sound groove of record *c* and starts the phonograph motor in the usual manner, whereupon, on each revolution of turntable *a*, gear 39 will be moved one step in a counterclockwise direction. When turntable *a* 35 has made the predetermined number of revolutions, the space 41 comes into the illustrated position so that gear 39 will no longer be actuated and arm 28 has swung 40 valve 29 into position to close the end of pipe 21. The closing of the latter will, as has been seen, permit the bellows 11, which heretofore has been collapsed to hold valve 10 in closed position, to move into the illustrated position and open valve 10, thereby 45 allowing motor *j* to start and music sheet *f* to be moved over the tracker-bar *i*. Thus, immediately as the sound reproductions are commenced by the phonograph, the accompanying 50 music is started by the player piano.

Thus, I have provided an apparatus whereby a separately-operable mechanism may be so controlled from a reproducing instrument that the mechanism may be 55 started simultaneously with the commencement of reproductions by the instrument, irrespective of the time of starting the record-carrying element of said instrument. It is recognized that various changes, substitutions and modifications may be made 60 in the one embodiment of the invention disclosed herein, and, inasmuch as I do not intend to restrict the scope of my invention except as necessitated by the prior art, 65 the scope of the invention is to be defined

by the appended claims rather than by the foregoing description.

What I claim is—

1. In combination, a record propelling means, reproducing mechanism, indicating 70 means permitting the record to be set relatively to the reproducing means so that reproductions commence after the record has been moved a predetermined distance, a second mechanism, and means independent of 75 the first mechanism and its record for starting the second mechanism simultaneously with the reproductions of the first mechanism and after the first-named means has moved the record said distance. 80

2. The combination in a phonograph with the rotatable record carrier thereof, of a controlling device adapted for connection to a separately-operable mechanism and adapted when in one position to permit the 85 starting of said mechanism, means to set said device to various other positions in any of which said device is adapted to prevent starting of said mechanism, and means controlled by the movement of said carrier to 90 move the device from any of the last-named positions into the first-named position, all constructed and arranged so that the mechanism may be started after the carrier has moved a predetermined distance. 95

3. In combination, two separately-operable musical instruments, a record-propelling means for each, and means controlled by one of said means to prevent starting of the other means until the first means has 100 moved its record a predetermined distance.

4. In combination, an automatic piano, a record-propelling motor therefor, connections between said motor and a source of supply for its actuating medium, a phonograph including its record-propelling means, means manually movable to various positions in each of which said motor is cut off from its supply, said means being automatically movable with said propelling 105 means to connect the motor with its supply after the record-propelling means has been moved a predetermined distance.

5. The combination in a sound-reproducing machine with its record-propelling means, of a device adapted for controlling the operation of a separate mechanism, said device including co-operating and relatively movable parts which when in one predetermined position are adapted to cause the 115 starting of said separate mechanism, manually operable means to move one of said parts to various other positions in each of which the controlling device is ineffective to start said separate mechanism, and automatic means to move said parts the one 120 relatively to the other into said predetermined position during the movement of said propelling means, whereby said separate mechanism may be started after a prede- 125 130

terminated movement of the record propelling means.

6. The combination in a reproducing machine with its record-propelling means, of a controlling device including a movably-mounted valve, a valve seat therefor, means permitting the valve to be moved away from its seat to various predetermined posi-

tions, and automatic means operable during the movement of the first-named means to move the valve until it is engaged with its seat, all constructed and arranged so that the valve may be seated at a predetermined time after the starting of said propelling means.

FREDERICK A. HOSCHKE.
